UNITED STATES PATENT OFFICE.

FREDERICK E. WALTER, OF BOGOTA, NEW JERSEY.

DESIGN FOR A FINGER-RING.

SPECIFICATION forming part of Design No. 24,916, dated November 26, 1895.

Application filed October 8, 1895. Serial No. 565,080. Term of patent 3½ years.

To all whom it may concern:

Be it known that I, FREDERICK E. WALTER, a citizen of the United States, and a resident of Bogota, in the county of Bergen and State 5 of New Jersey, have invented and produced a new and original Design for Finger-Rings, of which the following is a specification, reference being had to the accompanying drawings, forming part thereof.

10 In the drawings forming part of this application, Figure 1 is a perspective view of a ring embodying my new and original design, and Fig. 2 a side view thereof, these two parts being necessary to illustrate my design.

15 The leading feature of my design consists in the ring A, the upper portion of which on each side is provided with or has formed thereon the half of a wheel, as shown at B, the tire or rim of the wheel being directed 20 outwardly and the spokes inwardly, and at each side of the lower portion thereof the sides of the ring are provided with ornamental configuration, as shown at C, and above this ornamental configuration and extending from 25 the central portion of the wheel upwardly and inwardly on both sides are wings D, the points of which touch and support the setting E of a stone or other ornament or jewel F, said setting being also supported by a fork G, which 30 incloses the upper portion of the wheel and is provided with a shank which is connected with the base or bottom portion of the setting.

35 It will be understood that one of the forks G is arranged on each side and extends to the

central portion of the wheel inside of the wings D and that the shanks thereof are directed inwardly and upwardly and connect with the setting E, as above described.

The wheels B, or the halves of wheels, which 40 constitute a part of my design, are intended to represent bicycle-wheels, and the forks G the forks which form a part of the bicycle-frame, and my design is intended to represent a bicycle-ring and for use by those who 45 are in the habit of riding such machines or connected with the construction or manufacture thereof.

The ornamental configuration C at each 50 side of the lower portion of the wheels B may be of any desired form, the leading features of my design consisting, as hereinbefore stated, of the ring provided with a representation of bicycle-wheels, the wings D at each side thereof, forks G, and the setting or support for the stone F, together with said stone. 55

Having fully described my invention, I claim and desire to secure by Letters Patent—

60 The design for a ring herein shown and described.

In testimony that I claim the foregoing as my invention I have signed my name, in presence of the subscribing witnesses, this 4th day of October, 1895.

FREDERICK E. WALTER.
